UNITED STATES PATENT OFFICE.

DUNCAN McMILLAN, OF BROOKLYN, NEW YORK.

DESIGN FOR A STRAP-END ATTACHMENT.

SPECIFICATION forming part of Design No. 35,517, dated December 31, 1901.

Application filed November 15, 1901. Serial No. 82,455. Term of patent 14 years.

To all whom it may concern:

Be it known that I, DUNCAN McMILLAN, a citizen of the United States, residing at Brooklyn, New York, have invented and produced 5 a new and original Design for a Strap-End Attachment, of which the following is a full, clear, and exact description.

My invention relates to a new and original design for a strap-end attachment.

10 In the drawings, Figure 1 is a plan view, Fig. 2 is a side elevation, and Fig. 3 is an end elevation.

A is the main part, having a hole B for a rivet in one end. The other end is bent over 15 at C and terminates in prongs D D at right angles to the body part A. The curved part C, together with the body A and prongs D D, gives the appearance of a closed loop when

viewed in side elevation, which loop is substantially shorter than the full length of the 20 finished article.

The leading feature of my design consists in the body part bent over and terminating in prongs which stand adjacent the body in the finished article. 25

Having described my invention, what I claim as new, and desire to secure by Letters Patent, is—

The design for a strap-end attachment, as herein shown and described. 30

Signed at New York, N. Y., this 7th day of November, 1901.

DUNCAN McMILLAN.
